UNITED STATES PATENT OFFICE.

MICHAEL WLAAT, OF NEW YORK, N. Y.

AUTOMATIC GAS-VALVE.

No. 868,550.

Specification of Letters Patent.

Patented Sept. 17, 1907.

Application filed August 18, 1906. Serial No. 331,143.

To all whom it may concern:

Be it known that I, MICHAEL WLAAT, a citizen of the United States, residing at New York, in the county of New York and State of New York, have invented 5 new and useful Improvements in Automatic Gas-Valves, of which the following is a specification:

The invention relates to an improvement in automatic valve controllers, and particularly to an electrically-controlled means for operating the valve of 10 an ordinary gas burner.

The main object of the invention is the provision of a device which may be readily applied to the ordinary gas fixture without material change and which 15 may be utilized as a means for turning on or off the gas from any determinate point remote from the fixture.

The preferred details of construction will be described in the following specification, reference being had to the accompanying drawings, in which:

Figure 1 is a view in side elevation illustrating the 20 application of my improved valve controller, one of the movable magnets being shown at operative position. Fig. 2 is a sectional view on the line 2—2 of Fig. 1. Fig. 3 is a sectional view on the line 3—3 of Fig. 1. Fig. 4 is a diagrammatic view, illustrating 25 the wiring for the valve controller.

Referring particularly to the drawings, my improved valve controller includes two sets of electro-magnets 1 and 2, each set including two electro-magnets, as 3 and 4. The electro-magnets of each set are supported 30 with their cores in alignment, as clearly shown, and the relatively forward magnet of each set is movably mounted, as will presently appear. The means for supporting the magnets includes segmental plates 5 connected and held in spaced relation by a pair of 35 parallel rods 6 secured at their ends in the respective plates. Each of the plates is formed with an opening to receive the supply pipe 7 of a gas fixture, set screws 8 being provided in each plate for co-operation with the pipe to secure the segmental plates in fixed relation thereto. The rods 6 provide a means for supporting 40 the relatively forward magnet of each set, said magnets being each provided with encircling bands 9 projecting above the magnet proper in the form of ears 10, centrally perforated to slidably embrace the 45 respective rods. The rear magnet 4 of each set is supported through the medium of arms 11 pendent from the relatively rear segmental plate 5. As thus described, the magnets are supported in alignment immediately beneath the supply pipe of the gas fixture, 50 the forward magnet of each set being movably supported upon the respective frame rod 6.

The stem 12 of the usual gas cock 13 is provided on its lower end with a pinion 14, and the core of each of the forward magnets 3 is projected in the form of a rack-bar 15, the respective magnets being so spaced 55 as to provide for engagement of the rack bars with diametrically opposed teeth of the pinion 14, as clearly shown in Fig. 2.

The magnets of each set are energized through conductors 16 and 17 respectively, the former leading from a source of energy as a battery 18, and the latter terminating in contact points 19. A manually operable switch 20 is also in circuit with the battery and adapted to engage either of the contact points 19 at the will of the operator. As the relatively forward 65 magnet of each set is movably mounted, it is at once apparent that energizing the magnets of a particular set will cause the fixed magnet to attract the particularly movable magnet, the attraction being augmented by the magnetic influence of the movable magnet. 70 As the particular magnet 3 moves under the influence described, the rack-bar 15 is likewise moved, with the effect to operate the gas cock 13 through movement of the pinion 14. As either set of magnets 1 or 2 may be energized at the will of the operator, it is 75 obvious that the valve may be moved to open or close the same, as desired.

The attachment requires the addition of the pinion 14 to the ordinary gas cock and the application of the device to the supply pipe immediately in rear of said 80 gas cock, all other parts of the fixture remaining in their usual form. The device is thus readily applied to any of the ordinary gas cocks, as the addition of the pinion 14 in place of the usual thumb-piece, is readily accomplished.

It is, of course, obvious that the controlling switch 85 may be disposed at any point desired without regard to the fixture so that the gas may be readily turned on or off without necessitating the usual manual manipulation of the gas cock.

Having thus described the invention, what I claim is:—

1. The combination with a gas fixture, of a frame removably secured thereon, two sets of magnets supported by the frame, means for energizing either set of magnets at will, each set of magnets including a fixed magnet and a movable magnet, a pinion carried by the stem of the gas cock, and rack-bars projecting from the movable magnet of each set and engaging the pinion. 95

2. The combination with a gas fixture including a valve, 100 of a frame removably secured thereon, two sets of magnets supported by the frame, means for energizing either set of magnets at will, each set of magnets including a fixed magnet and a movable magnet, a pinion carried by the

stem of the gas cock, and rack-bars projecting from the movable magnet of each set and engaging the pinion, said rack-bars respectively engaging the pinion at diametrically opposite points, whereby to operate the valve in either direction in accordance with the set of magnets energized.

3. The combination with a gas fixture including a valve, of a frame removably secured thereto, said frame including spaced slide rods, independent magnets fixed to the frame, independent magnets movably supported on the respective

rods, one movable magnet and one fixed magnet being included in the same circuit, and means intermediate each movable magnet and the valve of the gas fixture.

In testimony whereof, I affix my signature in presence of two witnesses,

MICHAEL WLAAT.
